(57) **CLAIM**

The ornamental design of pumpkin jug, as shown and described.

DESCRIPTION

FIG. 1 is a perspective view of a pumpkin jug showing my new design;

FIG. 2 is a front elevation view of the pumpkin jug;

FIG. 3 is a rear elevation view of the pumpkin jug;

FIG. 4 is a right side elevation view of the pumpkin jug;

FIG. 5 is a left side elevation view of the pumpkin jug;

FIG. 6 is a top plan view of the pumpkin jug; and,

FIG. 7 is a bottom plan view of the pumpkin jug.

Where included, broken lines showing environment or structure are for illustrative purposes only and form no part of the design.

The broken lines in the drawing depict portions of the Pumpkin Jug that form no part of the claimed design.
